MASSAGING DEVICE

John W. Michaelson, Nisswa, Minn., assignor to
 Miracle Massage Appliances, Inc., Minneapolis,
 Minn., a corporation of Minnesota

Application November 17, 1939, Serial No. 305,017

5 Claims. (Cl. 128—57)

This invention relates to new and useful improvements in massaging devices, and more particularly to such a device adapted for use to massage the feet.

Attempts have heretofore been made to develop apparatus for massaging and treating the feet to relieve them of burning and aching sensations, which may result from various causes as, for example, wearing shoes which do not properly fit the feet, whereby the feet may be subjected to undue muscular tension and pressure, with the result that the nervous and circulatory systems of the feet may become affected. It is well known, that modern footwear, as commonly worn, does not always allow ample freedom for the feet, whereby the toes may be continually confined in a more or less cramped condition, while the shoes are worn.

I have found that the feet may be maintained in a comfortably healthy condition, and the metatarsal arch greatly strengthened, if the feet are periodically subjected to a massaging action whereby the bones of the metatarsus and the phalanges are so exercised as to stimulate blood circulation throughout the entire foot. To thus massage and exercise the feet, it is highly desirable that sufficient pressure be exerted against the ball of the foot, during each massaging operation, to cause the phalanges at the center of the foot to be pressed upwardly or out of their normal positions, in order to exercise the tissues and ligaments disposed therebetween. Such intermittent treatment of the phalanges results in increased blood circular and strengthening of the tissues and ligaments between the bones, as well as the muscles of the foot. To accomplish the above results, it is therefore highly essential that the massaging device to be used is so constructed that sufficient pressure may be exerted against the bottom of the foot to adequately exercise the bones of the metatarsus and the phalanges, and whereby substantially the entire foot may be subjected to a more or less vigorous, yet comfortable massaging action.

One of the important objects of the present invention, therefore, is to provide a massaging device which is capable of treating the feet as above stated, with very little effort on the part of the patient or person using it, and which, if periodically used to massage or treat the feet, will cause the feet to attain and maintain a healthy, comfortable condition.

A further object of the invention is to provide a massaging device of extremely simple and inexpensive construction, which may be supported on

a floor, in readiness for immediate use by an individual, any time such individual may desire treatment.

A further object is to provide an apparatus of the class described, comprising a suitable supporting frame having a plurality of resilient balls mounted thereon in juxtaposed relation, and adapted for rotation on axes which are inclined with respect to one another, and a plurality of other balls being arranged adjacent to said first mentioned balls and cooperating therewith to provide a passage adapted to receive a foot or other member to be treated, and certain of said balls being mounted for movement in a direction to permit enlargement of said passage against the action of suitable tension means, when a foot is inserted into said passage, whereby all of said balls may cooperate to exert a comfortable massaging pressure against the foot, the unique arrangement of certain of said balls being such that when the foot is moved back and forth in said passage, said balls will exert alternate lateral pulling and drawing actions on the flesh, which greatly stimulates the nervous and circulatory systems of the foot.

A further object is to provide a massaging device comprising a suitable frame having a plurality of resilient balls mounted thereon in substantially a given plane, and all of said balls being rotatably supported on a plurality of inclined axes which are so arranged as to cause the balls to be disposed in a more or less circular formation, with the peripheries of contiguous balls contacting each other, and whereby an opening or passage is provided between said balls adapted to receive a foot or other member to be treated, certain of said balls being yieldably retained in position under tension, whereby when a foot is inserted into said passage, said yieldably supported balls may yield to the pressure of the foot thereagainst, thereby to permit enlargement of the passage to accommodate the foot, and whereby all of the balls will cooperate to exert pressure against the foot from substantially all sides, in a manner to impart a comfortable, soothing, massaging action thereon.

A further object is to provide an apparatus of the class described, including a group of resilient balls, comprising a central ball mounted for rotation on a horizontal axis, and a pair of balls mounted on inclined axes at the sides of said central ball with their peripheries contacting the periphery of the central ball, and a second group of resilient balls being mounted over said first group of balls with their peripheries normally

contacting the peripheries of some of the balls of said first group of balls, said upper balls being mounted on a resilient support, whereby when a foot is inserted between the balls of said groups of balls, the upper resilient balls may move away from the lower balls to permit passage of the foot between said balls, said resilient support causing the balls to exert a pressure against the foot from substantially all sides thereof, so that 10 the entire foot is massaged when moved back and forth in the passage provided between said balls.

A further object is to provide a massaging device comprising a frame having a plurality of resilient balls mounted thereon and arranged in 15 substantially circular formation with the peripheries of contiguous balls contacting one another, and whereby a passage is provided between said balls adapted to receive a foot, and an auxiliary ball being rotatably supported in spaced relation 20 to said first mentioned balls adapted to engage the bottom of the foot and impart a massaging action thereto, when the foot is moved back and forth in said passage.

A further object is to provide a massaging device which is an improvement over the form disclosed in Patent No. 2,168,842, granted to Charles E. Kestevan and John W. Michaelson, August 8, 1939.

Other objects of the invention reside in the 30 simple and inexpensive construction of the apparatus, whereby it may be manufactured at small cost; in the novel arrangement of the resiliently mounted upper balls, whereby when a foot is inserted in the passage provided between the groups of balls, all of said balls will exert a massaging pressure against the foot from substantially all sides thereof; in the provision of the auxiliary ball which engages the bottom of the foot, which is so arranged that the pressure exerted against 40 the bottom of the foot by said ball, may readily be controlled by the individual using the device, by simply varying the downward pressure of the foot thereon; and, in the provision of such a device which is so constructed that when placed 45 upon a floor, a person may readily and conveniently move the foot back and forth in the opening defined by said resilient balls, with the bottom of the foot engaging said auxiliary ball, thereby massaging and manipulating the entire foot in 50 such a manner that the metatarsus and phalanges are so exercised as to strengthen the tissues and ligaments therebetween, and whereby the nervous and circulatory systems of the foot are also greatly stimulated.

Other objects of the invention will appear from 55 the following description and accompanying drawing and will be pointed out in the annexed claims.

In the accompanying drawing there has been 60 disclosed a structure designed to carry out the various objects of the invention, but it is to be understood that the invention is not confined to the exact features shown as various changes may be made within the scope of the claims which 65 follow.

In the drawing:

Figure 1 is a plan view of a massaging device embodying my invention;

Figure 2 is a side elevation of Figure 1, partially broken away, and showing the balls in their normal positions;

Figure 3 is a rear view of the device showing the circular arrangement of the resilient balls, when in normal position;

Figure 4 is a sectional elevation on the line

4-4 of Figure 1, showing a foot positioned between the balls; and

Figure 5 is a detail sectional view showing the action of the auxiliary ball on the bottom of the foot, during the massaging operation.

In the selected embodiment of the invention here shown, there is illustrated in Figures 1 to 4, inclusive, a massaging device comprising a main supporting frame, generally indicated by the numeral 2. This frame, as here shown, is constructed of a metal rod bent upon itself to provide diverging arms or side members 3-3, having cushion elements or feet 4 secured to the rear ends thereof. A cross member 5 retains the rear end portions of the arms or side members 3-3 in 15 spaced relation.

The means for engaging and massaging the foot is shown comprising a plurality of resilient balls which are rotatably supported in the frame 2. In the present instance, six balls are utilized, 20 five of which are arranged in circular formation with the peripheries of contiguous balls in direct contact with one another. The circularly arranged group of balls, as shown in Figure 3, consists of a center or bottom ball 6, side balls 7-7 and upper balls 8-8. The lower ball 6 is rotatably supported on a horizontally disposed axis 9, and the side balls 7 are similarly supported upon inclined axes 10-11, secured to spaced arms 12, shown formed from a single piece of 30 suitable wire or rod, bent upon itself to form a loop 13, which may be secured to the looped end 14 of the main supporting frame 2 by a suitable bolt or screw 15, best shown in Figure 4. Suitable clamping plates 16 and 17 are provided 35 above and below the looped ends 13 and 14 of the arms 12 and the main frame 2, which cooperate with the bolt 15 to secure the parts together. In the structure, as above described, the side balls 7-7 are so arranged with respect to the rear 40 center or bottom ball 6, that when the foot is moved in one direction in said opening, the balls 6 and 7 impart a lateral pulling action on the flesh, and when moved in the opposite direction in said opening, a compression action is imparted 45 to the flesh. This particular construction is clearly shown and described in the hereinbefore mentioned patent.

A feature of the present invention resides in the novel arrangement of the upper balls 8-8. 50 These balls, as clearly illustrated in Figures 2, 3, and 4, are supported upon axes 18 which are inclined with respect to each other, as clearly illustrated in Figure 3, the angular relationship between said axes being such that the peripheries 55 of the upper balls substantially contact each other. The axes 18 may be formed by a suitable rod or bolt 19, bent at its intermediate portion and having its terminals secured to the ends of a pair of resilient arms 21, preferably formed of a 60 piece of spring wire, bent upon itself to provide a central loop 22 which is traversed by the bolt 15 to secure the arms 21 to the main frame, as clearly shown in Figures 2 and 4. The resilient arms 21 are preferably provided with suitable coils or 65 loops 23 which serve, in effect, as coil springs, to constantly exert a downward force on the upper balls 8-8 to normally hold them in contact with the peripheries of the side balls 7-7, as best shown in Figure 3. The balls 6, 7, and 8, when in 70 normal positions, as shown in Figures 2 and 3, are disposed in substantially circular formation, whereby they cooperate to provide a passage 24 adapted to receive a foot or other member to be treated, as clearly illustrated in Figure 4.

Another feature of the invention resides in the provision of an auxiliary ball 25 which is mounted forwardly of the balls 6, 7, and 8, upon a cross shaft or rod 26, the terminals of which are shown supported in suitable loops 27 provided in the side members 3 of the main frame 2. The ball 25 is relatively harder or less resilient than the balls 6, 7, and 8, and is adapted to contact the bottom of the foot, as clearly illustrated in Figures 4 and 5. The ball 25 is rotatably supported on the shaft 26 and is disposed forwardly of the rear center ball 6 in such a manner that when the foot is inserted in the passage 24 and moved forwardly and backwards therein, the bottom of the foot may engage the auxiliary ball 25 with sufficient pressure to upwardly press the bottom of the foot, as shown in Figure 5, and thereby displace the metatarsal bones and phalanges from their normal positions, as clearly illustrated in Figure 5. The balls 6, 7, and 8 are preferably constructed of a soft, resilient material, such as sponge rubber, whereas the auxiliary ball 25 is of a relatively harder material or rubber.

When the device is to be used, it is preferably placed upon the floor, and the individual then inserts a foot into the passage 24 defined by the balls 6, 7, and 8. As the foot is thrust forwardly in the opening 24, the upper balls 8 will yield to the pressure of the foot, as shown in Figure 4, thereby permitting the bottom of the foot to engage the auxiliary ball 25. The foot is moved back and forth between the balls, as shown in the full and dotted lines in Figure 4, whereby the balls 6, 7, and 8 will impart a massaging action to the top, bottom, and sides of the foot, while, at the same time, the auxiliary ball 25 will exert a very definite upward pressure against the bottom of the foot, as shown in Figure 5, whereby the bones of the foot are exercised and a massaging action imparted to the entire foot, which will greatly stimulate circulation and strengthen the tissues and ligaments of the foot.

The device, as shown, is substantially self-supporting, when placed upon the floor, so that the user may readily move his foot back and forth between the balls thereof, with utmost ease and comfort, whether disposed in a sitting or standing position.

As shown in Figure 4, a suitable rubber element 28 may be engaged with the lower end of the bolt 15, and a secondary bolt 29 may also be interposed between the forward ends of the arms 21 and the lower clamping plate 17. Adjustment of the bolt 29 may vary the tension in the arms 21.

In the structure as herein shown and described, but one ball, such as 25, is utilized. It is to be understood, however, that in some cases, it may be deemed advisable to place another ball (not shown) forwardly of the auxiliary ball 25, adapted to cooperate with the latter to further massage and exercise the bottom of the foot. It is also

to be understood that the balls 6, 7, 8 and 25, need not necessarily be spherical in shape, as obviously their shapes may be somewhat varied without affecting the efficiency of the apparatus. The main supporting frame 2 may also be otherwise constructed without departing from the scope of the invention.

I claim as my invention:

1. A foot massaging device comprising a supporting structure having a plurality of feet, a main supporting frame on said feet, and a cross shaft mounted in said supporting frame and approximately mid-way between the feet; a pair of arms supported by said frame and the cross shaft; a plurality of resilient balls mounted for rotation on said arms; an auxiliary ball mounted on said cross shaft; resilient arms mounted from one of said feet and extending under the cross shaft and upwardly above said shaft; and a plurality of resilient balls mounted on said resilient arms, said first mentioned balls and the auxiliary ball engaging the bottom of the foot to be massaged and the last mentioned balls on the resilient arms contacting the upper portion of the foot to be massaged to facilitate and force engagement of the foot with the first mentioned and auxiliary balls.

2. A foot massaging device according to claim 1, in which the auxiliary ball is relatively harder than the other balls.

3. A foot massaging device according to claim 1, in which means are provided for supporting the resilient arms with spring tension from said foot on which the resilient arms are mounted.

4. A foot massaging device according to claim 1, in which means are provided for the resilient arms secured to said foot on which the resilient arms are mounted to support said resilient arms with spring tension, said means including a pair of clamping plates and a pair of bolts to vary the tension in the resilient arms by adjustment of one of the bolts.

5. A foot massaging device comprising a supporting structure having a plurality of feet, a main supporting frame on said feet, and a cross shaft mounted in said supporting frame and approximately mid-way between the feet; a pair of arms supported by said frame and the cross shaft; a plurality of resilient balls mounted for rotation on said arms; an auxiliary ball mounted on said cross shaft; resilient arms mounted on said frame at one end and extending above said shaft at the other end; and a plurality of resilient balls mounted on said resilient arms, said first mentioned balls and the auxiliary ball engaging the bottom of the foot to be massaged and the last mentioned balls on the resilient arms contacting the upper portion of the foot to be massaged to facilitate and force engagement of the foot with the first mentioned and auxiliary balls.

JOHN W. MICHAELSON.
